1,941,647

PROCESS FOR THE MANUFACTURE OF
ETHER DERIVATIVES OF 1-BENZYL-3-
METHYL-ISOQUINOLINE

Otto Wolfes, Darmstadt, Germany

No Drawing. Application July 19, 1930, Serial
No. 469,262, and in Germany August 24, 1929

9 Claims. (Cl. 260—25)

This invention relates to the manufacture of compounds of therapeutic value.

It is known (Bischler & Napieralski, Ber. der deutschen chem. Gesellschaft 26 (1893) 1903, Pictet & Finkelstein, Ber. d. deutschen chem. Gesellschaft 42 (1909) 1979) that acid amides which have been obtained by the interaction of phenylacetic acids and 1-phenyl-2-aminoethanes, can often be converted into 1-benzylidene-¹⁰ hydro-isoquinolines under the influence of condensing agents such as zinc chloride, phosphorous pentoxide, phosphorous oxychloride.

That this reaction does not always take place, but is influenced by certain groups of atoms, is evident from a work by Callow, Gulland and Haworth (Journ. Chemic. Soc. London, 1929, p. 1444). An acetylene derivative having an open chain was obtained instead of the expected isoquinoline derivative. Similarly experiments of Gadamer, Oberlin, Schöler (Archiv. d. Pharm. 263 (1925) 3 para 2) met with negative results. It was therefore not to be foreseen whether isoquinoline with an alkyl-group in position 3 could be prepared according to the above mentioned process.

It has been found by experiment that acid amides which contain as basic components, for example, 1-(3',4'-methylene-dioxyphenyl)-2-amino-propane (German Patent 274,350) are able to close the dihydro-isoquinoline ring under the influence of condensing agents. If in this reaction the acid components are derivatives of phenyl-acetic acid or ethers of oxy derivatives of phenylacetic acid then bases of papaverine-like constitution and physiological action are obtained by dehydrogenation. Some of them are distinguished from papaverine by a more favorable therapeutic index. This was not to be expected because the compounds analogous to papaverine which were already known were not advantageous for medicinal purposes (Mannich & Walter, Archiv. d. Phar. 265 (1927) p. 3).

Furthermore it has been found that the condensation takes place at temperatures from 45 60-150°, the dehydrogenation takes place at 160-220°; more especially the most advantageous temperature for carrying out the condensation is about 105°, while the dehydrogenation preferably is carried out at about 180° C. Although any acid condensing agent may be used it has been found that phosphorous oxychloride is the most suitable condensing agent. The pointed out temperatures of 105° and 180° C. and the mentioned condensing agent together secure the best yields.

55 The dehydrogenation may be carried out in an

advantageous way only with palladium as catalyst.

As already mentioned the new products are of especial therapeutic value. Particularly 1-(3',4'-methylene-dioxybenzyl)-3-methyl-6,7-methylenedioxyisoquinoline has proved to be of high pharmaceutical value. This compound is manufactured as shown in Example 1, shows a melting point of 141°, is soluble in chloroform, hot alcohol and hot ether, difficultly soluble in cold alcohol and cold ether, insoluble in water.

It was already known that di- and tetrahydropapaverine can be dehydrogenated to papaverine by means of palladium (Spaeth u. Burger, Ber. der deutschen chem. Gesellschaft 60 (1927), 70 704), but in this case both the carbon atoms, whose single bond is to be converted into a double bond, carry two hydrogen atoms. In the present case it is a question of dehydrogenation in which one of each of the hydrogen atoms is replaced by an alkyl group whereby the dehydrogenation could be made difficult and in certain circumstances impossible. As to how little such dehydrogenations were to be foreseen according to literature up to the present, is shown by the work of Shirō Akabori and Tazō Suzuki (Proceed. Imp. Acad. Tokyo 5, 255) who were unable to dehydrogenate tetrahydropapaverine as is expressly mentioned by the authors.

Examples

85

(1) 10 parts of the amide

90

(prepared from 1-(3',4'-methylene-dioxyphenyl)-2-aminopropane and homopiperonylic acid, melting point=146°) are dissolved in 180 parts of hot toluene and heated with 6 parts of phosphorous oxychloride for 3 hours to about 100° C. The reaction product, which separates out as a dark partly crystalline mass, is separated from the toluene and stirred with 100 parts of water and heated for half an hour, filtered with carbon and allowed to crystallize. The hydrochloride of the new base separates off in prisms which melt at 237° C. with decomposition. The hydrochloride is separated by crystallization and sucking off. The free base is obtained by adding alkali to the solution of the hydrochloride, taking the reaction product up with ether and evaporating the solution to crystallization. It melts at 103° C. 10 parts of the same are stirred with 1 part of palladium black for 3 hours at about 180° C. The fused mass is dissolved in hot 4 per cent hydrochloric acid, puri-

105

110

fied with charcoal and allowed to crystallize. The hydrochloride separates off in prisms which contain water of crystallization and melt in an anhydrous state at 254° C. (with decomposition). The free base crystallizes out from methanol in brilliant prisms having a melting point 141° C.

The yield amounts to about 90% of the theoretical on closing the ring and 75% of theoretical on dehydrogenation.

10 The reaction and structural formulas are illustrated below:

(2) 10 parts of the amide

(CH₃O)₂C₆H₃—CH₂—CH(CH₃)—
45 NH—CO—CH₂—C₆H₅

are dissolved in 150 parts of toluene with heating, and after the addition of a mixture of 10 parts of phosphorous pentoxide in 20 parts of toluene, the solution is boiled. After cooling the reaction 50 product is stirred, after separation of the toluene, with 100 parts of water, boiled with charcoal, filtered and the hydrochloride of the new base is separated out by adding common salt.

55 The temperatures used and other measures are the same as in Example 1.

The free base is, as described in Example 1, dehydrogenated by heating with palladium. The average yield is 60%. The melting point of the 60 new base is 109° C.

65 The structural formula is as follows:

(3) 150 parts of the amide

(CH₃O)₂C₆H₃—CH₂—CH(CH₃)—
75 NH—COCH₂—C₆H₃(OCH₃)₂

(prepared from 1-(3', 4'-dimethoxy-phenyl)-2-aminopropane and 3, 4 dimethoxyphenyl-acetic acid (homoveratric acid) are dissolved in 1500 parts of hot toluene and heated with 130 parts of phosphorous oxychloride for 6 hours to 100° C. After separating the toluene the reaction product is dissolved in hot water, filtered with charcoal and worked up to the free base by adding ammonia solution. This base is obtained as a thick oil by taking up in ether, filtering with charcoal and distilling off the ether. The methylpapaverine is obtained by heating this oil with one-fourth part of its weight of palladium to about 180°. The end product (methyl papaverine) melts, after redissolving from alcohol, at 136°. The hydrochloride crystallizes with water of crystallization. It is obtained in an anhydrous state by crystallizing from alcohol and melts at about 234° with decomposition. The average yield is 60%.

80 The structural formula of methyl-papaverine is as follows:

(4) 10 parts of the amide

(CH₃O)₂C₆H₃—CH₂—CH(CH₃)—
100 NH—CO—CH₂—C₆H₃(O₂CH₂)

(prepared from 1-(3'-4'-dimethoxyphenyl)-2-aminopropane and homopiperonylic acid having a melting point 110°) are dissolved in 150 parts of xylene and, after the addition of 10 parts of phosphorous oxychloride, heated to 125° C. The reaction product is worked up to the free base which is dehydrogenated by heating with 10% of palladium black to 190° C. The isoquinoline derivative is repurified from boiling ether. The base melts at 168—169° C. The hydrochloride (crystallized from absolute alcohol) melts at about 233° C. with decomposition. The average yield is 60%.

115 The structural formula is as follows:

(5) 10 parts of the amide

(CH₂O₂)C₆H₃—CH₂—CH(CH₃)—
130 NH—CO—CH₂—C₆H₃(OCH₃)₂

(melting point=123°) are converted by heating to about 100° with phosphorous pentoxide in a solution of xylene into the dihydroisoquinoline derivative which is dehydrogenated with palladium black at about 180° C. The isoquinoline base melts, after purification from ether, at 125° C. and the hydrochloride at about 220° C. with decomposition. The average yield is 60%.

145

150

The structural formula is as follows:

5 15 (6) 10 parts of the amide

(prepared from 1-(3',4'-methylenedioxyphenyl)-2-aminopropane and ethyl phenylacetic acid, melting point=138°) are dissolved in 20 parts of hot toluene and heated with 8 parts of phosphorous oxychloride for 3 hours to 105° C. The reaction product is worked up to a free base, which is dehydrogenated with palladium black at about 180° C. and redissolved from alcohol. The substance separates in colorless leaflets which melt at 143°. The hydrochloride is very difficultly soluble in water and melts at about 80° C. Average yield is 70%.

30 The structural formula is as follows:

I claim:

45 1. As a product 1-(3',4'-methylenedioxybenzyl)-3-methyl-6,7-methylenedioxyisoquinoline, a substance soluble in chloroform, hot alcohol and hot ether, difficultly soluble in cold alcohol and cold ether, insoluble in water, showing a melting point of 141° C., while the hydrochloride of this base melts at 254° C. (under decomposition); the free base showing crystals of brilliant prisms.

50 55 2. Process for the production of a 1-benzyl-3-methyl-6,7-dialkoxy-isoquinoline consisting in condensing a phenylacetic acid with 1-(3',4'-dialkoxyphenyl)-2-amino-propane, treating the amide thus obtained with acid condensing agents at a temperature of about 60-150° C.; separating the crystalline hydrochlorides of the bases thus obtained; liberating the free bases from the hydrochlorides by the addition of alkali; and heating the bases with palladium black to about 160-220° C. for the purpose of dehydrogenation.

60 65 3. Process for the production of a 1-(3',4'-dialkoxybenzyl)-3-methyl-6,7-dialkoxy-isoquinoline consisting in condensing a 3,4-dialkoxyphenylacetic acid with a 1-(3',4'-dialkoxyphenyl)-2-amino-propane, treating the amide thus obtained with acid condensing agents at a temperature of about 60-150° C.; separating the crystalline hydrochlorides of the bases thus obtained; liberating the free bases from the hydrochlorides by the addition of alkali; and heating the bases with palladium black to about 160-220° C. for the purpose of dehydrogenation.

75 4. Process for the production of a 1-benzyl-3-

methyl-6,7-dialkoxy-isoquinoline consisting in condensing phenylacetic acid and a 1-(3',4'-dialkoxyphenyl)-2-amino-propane, treating the amide thus obtained with phosphorus oxychloride at a temperature of 105° C.; separating the crystalline hydrochlorides of the bases thus obtained; liberating the free bases from the hydrochlorides by the addition of alkali; and heating the bases with palladium black to about 180° C. for the purpose of dehydrogenation.

80 85 5. Process for the production of a 1-(3',4'-dialkoxybenzyl)-3-methyl-6,7-dihydroxy-isoquinoline consisting in condensing a 3,4-dialkoxyphenylacetic acid with a 1-(3',4'-dialkoxyphenyl)-2-amino-propane, treating the amide thus obtained with phosphorus oxychloride at a temperature of 105° C., separating the crystalline hydrochlorides of the bases thus obtained; liberating the free bases from the hydrochlorides by the addition of alkali; and heating the bases with palladium black to about 180° C. for the purpose of dehydrogenation.

90 95 6. Process for the production of 1-(3',4'-methylenedioxybenzyl)-3-methyl-6,7-methylenedioxy-isoquinoline, consisting in condensing homopiperonylic acid and 1-(3',4'-methylenedioxyphenyl)-2-amino-propane, treating the amide thus obtained with acid condensing agents at a temperature of 60-150° C., separating the crystalline hydrochloride of the base formed in the preceding step, liberating the free base from the hydrochloride by the addition of alkali; and heating the base thus obtained with finely divided palladium black to 160-220° C. for the purpose of dehydrogenation.

100 105 7. Process for the production of 1-(3',4'-methylenedioxybenzyl)-3-methyl-6,7-methylenedioxy-isoquinoline, consisting in condensing homopiperonylic acid and 1-(3',4'-methylenedioxyphenyl)-2-amino-propane, treating the amide thus obtained with phosphorus oxychloride at a temperature of 105° C., separating the crystalline hydrochloride of the base formed in the preceding step, liberating the free base from the hydrochloride by the addition of alkali; and heating the base thus obtained with finely divided palladium black to 180° C. for the purpose of dehydrogenation.

110 115 8. Process which consists in treating an amide of the type represented by the formula,

120 125 130 135 where each X is hydrogen or alkoxy or both 140 stand for the methylenedioxy radical, and the Y's represent members of the group consisting of alkoxy and methylenedioxy, and the R stands for hydrogen or alkyl, with acid condensing agents at a temperature of about 60° C. to 150° C., separating the crystalline hydrochlorides of the bases thus obtained, liberating the free bases from the hydrochlorides by the addition of alkali, and heating the bases with palladium black to about 145 150 160-220° C. for the purpose of dehydrogenation,

the product being represented by the general formula:

5

10

15

wherein each $\mathbf{X}$ is hydrogen or alkoxy or both stand for the methylenedioxy radical, and the $\mathbf{Y}$'s

20

represent members of the group consisting of al-

koxy and methylenedioxy, and the $\mathbf{R}$ stands for

hydrogen or alkyl.

9. Process for the production of 1-(3',4'-dial-

80

koxybenzyl) 3-methyl-6,7-dialkoxy-isoquinoline,

85

consisting in condensing 3,4-dialkoxy-phenyl-

acetic acid with 1-(3',4'-dialkoxyphenyl)-2-

amino-propane, treating the amide thus obtained

with acid condensing agents at a temperature of

about 60-150° C.; separating the crystalline hy-

drochloride of the base thus obtained; liberating

the free bases from the hydrochlorides by the

addition of alkali; and heating the bases with

palladium black to about 160-220° C. for the pur-

pose of dehydrogenation.

OTTO WOLFES.
